UNITED STATES PATENT OFFICE.

CLARENCE B. FOWLER, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

Application filed August 27, 1923. Serial No. 659,509.

To all whom it may concern:

Be it known that I, CLARENCE B. FOWLER, a citizen of the United States of America, residing at New York city, in the county of 5 New York and State of New York, have invented certain new and useful Improvements in Telephone Systems, of which the following is a full, clear, concise, and exact description.

10 This invention relates to telephone systems and more particularly to operator's equipment employed in connection with machine switching telephone systems.

In systems of the above mentioned type, 15 an operator at a central office is required to handle various types of connections, the most common being local and toll switching connections. The establishment of a connection over a local switching trunk requires 20 a different condition of the dialing equipment than that required in establishing a toll switching connection, that is, the pulsing relay of a local trunk is generally supplied with battery from the trunk circuit 25 whereas the pulsing relay of a toll switching trunk receives battery from the dialing equipment.

It is an object of this invention to enable 30 an operator to establish various types of connections over trunk circuits having different electrical characteristics by employing the least possible apparatus and with the least possible delay and confusion.

This object is attained in accordance with 35 a feature of this invention by the provision of a universal cord circuit wherein a marginal relay is employed to discriminate between local and toll switching trunks to mechanical offices, to condition an associated dial circuit for operation with either of said trunks.

Another feature resides in the control of 40 signaling means by a called subscriber to indicate to an operator that she has failed to 45 restore the dial key subsequent to the establishment of a connection. The desirability of such an arrangement is readily seen when it is understood that the operation of the dial key splits the talking circuit so that 50 should a called party respond when the dial key was still operated, there would be no path for the transmission of voice currents and conversation between the called and calling parties would be impossible.

55 Other features will be readily discernible

from the following descriptions made with reference to the accompanying drawings; wherein,

Fig. 1 shows a cord circuit F embodying features of this invention and adapted to co- 60 operate with either a magneto line or a common battery line.

Fig. 2 shows an operator's telephone and dialing circuit.

Fig. 3 shows a local trunk circuit which 65 may be employed to automatically extend a connection to the common battery station.

Fig. 4 shows a toll switching trunk which 70 may be employed to automatically extend a toll connection to a subscriber's station.

Fig. 5 shows a subscriber's station and automatic switches by which a connection is extended thereto from the toll switching 75 trunk circuit of Fig. 4.

The automatic switches have been shown 80 schematically and only that part of the associated operating equipment which is necessary for a complete understanding of the invention has been disclosed in detail.

A call will first be traced from a calling 85 subscriber on the common battery station A to the subscriber's station P by way of the local trunk E. In order to trace through this connection Fig. 3 should be placed to the right of Fig. 1 and Fig. 2 immediately 90 above Fig. 1.

The subscriber at A on initiating a call removes the receiver from the switchhook whereupon a circuit is established for line relay 10 extending from grounded battery, 90 through the right hand winding of relay 10, inner armature and back contact of cut-off relay 11, over the subscriber's line loop and apparatus at station A, back contact and outer armature of relay 11, to ground 95 through the left hand winding of relay 10. Relay 10 operates in this circuit and establishes an obvious circuit for line lamp 12. The illumination of line lamp 12 indicates to the operator at the central office that a 100 call is awaiting her attention and she proceeds to answer it by inserting the answering plug 13 of the cord circuit F into jack 14 corresponding to the illuminated line lamp 12 and operating her talking key T. 105 Upon the insertion of plug 13 into jack 14, a circuit is established which may be traced from grounded battery, the winding of relay 15, winding of relay 16, sleeve contacts 110 of plug 13 and jack 14, to ground through 115

the winding of relay 11. Relays 11, 16 and 15 operate in this circuit. Relay 11 in operating disconnects the line relay 10 from the conductors of the calling line thereby causing it to release and extinguish line lamp 12. Relay 16 in operating performs no useful function at this time. Relay 15 in attracting its left hand and inner right hand armatures opens its normally closed contacts 5 moving the relay 17 and condenser 90 from in bridge of the left hand windings of repeating coil 19. This bridge is employed only in connection with calls originating at a magneto station. In closing the alternate 10 contacts, the above mentioned armatures of relay 15 connect ground and battery to the upper and lower left hand windings respectively, of repeating coil 19, the battery being supplied by way of the winding of relay 18. 15 This battery is used for talking purposes. Relay 18 operates in a circuit extending from grounded battery, winding of relay 18, front contact and left hand armature of relay 15, lower left hand winding of repeating coil 20 20, ring conductor of cord F, lower normal contacts of ringing key 91, ring contacts of plug 13 and jack 14, over the subscriber's line loop and apparatus at station A, tip contacts of jack 14 and plug 13, upper normal 25 contacts of ringing key 91, tip conductor of cord F, upper left hand winding of repeating coil 19, inner right hand armature and front contact of relay 15 to ground. Relay 18 operating in this circuit, prevents lamp 20 from illuminating at this time by connecting the battery 58 to the filament of lamp 20 which shunts out the battery normally associated therewith. At its outer right hand armature, relay 15 establishes a 30 circuit which may be traced from grounded battery, filament of lamp 20, left hand winding of relay 21, to ground over the outer right hand armature and front contact of relay 15. Relay 21 operates in this circuit but lamp 20 does not as hereinbefore 35 explained.

The ground connected to the alternate contact and outer right hand armature of relay 15 also causes relays 22 and 23 to operate in a circuit extending from grounded battery through the winding of relay 23, left hand winding of relay 22 to ground over the outer right hand armature and front contact of relay 15. Relay 23 in attracting its armatures connects the condenser 24 between the left hand windings of repeating coil 19 thereby rendering the answering end of the cord serviceable for a common battery connection. Relay 22 in operating breaks the direct connection between the answering and calling ends of the cord and connects them through the repeating coil 19.

The actuation of talking key T as hereinbefore mentioned connects the conductors 40 28 and 27 to the tip and ring conductors of

the answering end of the cord circuit and since these conductors are associated with the operator's telephone set, by way of the normal contacts of relay 29, the operator is in a position to converse with the calling 70 subscriber.

Upon learning that the desired party is located at substation P, the operator proceeds to reach the called subscriber's station in the following manner:—Having restored the talking key T, the operator tests for an idle local trunk, such as E. In making this busy test, the operator touches the tip of plug 30 to the sleeve of the trunk which, if busy, will be at battery potential, 75 whereupon a circuit will be established extending from battery potential on the sleeve of the trunk, tip of plug 30, continuity contacts of relay 32, conductor 34 to ground through the winding of relay 32. Relay 32 80 operates in this circuit whereupon a circuit is established extending from grounded battery, the winding of retardation coil 35, front contact and armature of relay 32, to ground through the right hand winding of 85 repeating coil 36. The operator's headset 99 is in series with the left hand winding of repeating coil 36 and induced current passing through this winding of coil 36, causes a click in her ear indicating to her 90 that the trunk circuit is busy. If an idle trunk is tested, no battery will be present on the sleeve. Relay 32 will not be energized and the click in the headset 99 will not be heard. 100

Assuming local trunk E to be idle, the operator inserts plug 30 into jack 31. The trunk circuit E being a local trunk has a low resistance sleeve. A circuit now exists extending from grounded battery, through the winding 105 of relay 36, winding of relay 37, sleeve contacts of plug 30 and jack 31, to ground through the winding of sleeve relay 38. Relays 38, 37 and marginal relay 36 operate in this circuit. Relay 37 establishes an obvious circuit 110 for relay 33 which on energizing disconnects the busy test relay 32 from the tip of the calling end of the cord and renders the tip conductor continuous at that point. At its lower armature, relay 33 performs no useful 115 function at this time. In attracting its outer left hand armature, relay 36 also establishes an energizing circuit for relays 22 and 23 so that the condition of the cord is now under control of both the answering and calling 120 ends of the cord. In attracting its inner left hand and right hand armatures, relay 36 disconnects the left hand winding of relay 96 from bridged relationship with the calling 125 end of the cord. The above mentioned armatures of relay 36 in closing their alternate contacts, connect battery and ground to the right hand winding of repeating coil 19, the battery being supplied by way of the winding of relay 39, which relay corresponds to 130

relay 18 in the answering end of the cord circuit. Relay 96 operates in series with lamp 53 in a circuit extending from grounded battery, through the filament of lamp 53, conductor 89, back contact and armature of relay 75, right hand winding of relay 96 front contact and outer left hand armature of relay 36 to ground over the front contact and armature of relay 37. The lamp 53 lights in this circuit since relay 39 is not operated at this time as will appear from the following description. Relay 38 operating over the sleeve circuit establishes an obvious circuit for slow-releasing relay 41. When the plug 30 is fully inserted in jack 31, relay 42 immediately operates over the ring side of the connection to grounded battery, through winding of relay 39. Relay 39 may momentarily energize in this circuit, but will be immediately released when relay 42 operates since in operating, relay 42 disconnects itself from the ring side of the trunk and locks itself to grounded battery on the armature and front contact of relay 41. Relay 42 at its outer left hand armature, connects cut-off relay 43 to the ring side of the trunk but this relay does not operate at this time. At its inner right hand armature, relay 42 causes the pulsing relay 44 to operate in a circuit extending from grounded battery, through the winding of relay 44, upper normal contacts of relay 43, to ground over the front contact and inner right hand armature of relay 42. Relay 44 in operating, connects retardation coil 51 and the windings of polar relay 45 across the mechanical switching end of the trunk E to prepare the selector S for stepping. At its outer armature, relay 42 connects a protective bridge, including condenser 46 and resistance element 46', across the pulsing contacts of relay 44. The trunk circuit is now in condition to receive dial pulses.

The operator now actuates the dialing key 40 and dials the required digits. The actuation of this key connects the tip and ring conductors of the calling end of the cord circuit to the conductors 95 and 48 respectively. In dialing, the dial off-normal contact is operated and cut-off relay 43 becomes energized in a circuit which may be traced from grounded battery, armature and front contact of relay 41, winding of relay 43, back contact and armature of relay 47, outer left hand armature and front contact of relay 42, ring contacts of jack 31 and plug 30, lower alternate contacts of key 40, conductor 48, back contact and left hand armature of relay 49, off-normal contact 93 of dial Q, back contact and inner left hand armature of relay 50 to ground over the outer right hand armature and back contact of relay 50. Cut-off relay 43 operates in this circuit and at its outer upper and lower armatures disconnects the manual end from the mechanical

switching end of the trunk. At its inner upper armature, relay 43 connects pulsing relay 44 to the tip conductor of the manual end of the trunk thereby placing it in position to receive the dial pulses. Owing to the make-before-break contacts of relay 43, relay 44 remains energized during its transfer to the tip conductor of the trunk. At its inner lower armature, relay 43 opens the circuit for relay 47 to ground at relay 45 and thus prevents it from being operated from the tip side of the connection. The operator now releases the dial so that the dial in returning to normal interrupts the pulsing contacts 54 of the dial Q a predetermined number of times. The successive opening and closing of the pulsing contacts of the dial Q interrupts the circuit for pulsing relay 44 so that it follows the interruptions of the dial and causes the opening and closing of the bridge across the mechanical switching end of the trunk which causes selector S to operate in a manner well known in the art. For a complete disclosure of an automatic system in which selectors are thus operated, reference may be had to Reissue Patent No. 13 901, F. Newforth, jr., April 13, 1915.

Between operations of the dial and after the dial returns to normal, cut-off relay 43 releases restoring the circuit to its condition prior to the actuation of relay 43. Relay 44 remains energized over its original energizing circuit.

In order to simplify the description and since a complete description of the operation of such selectors and connectors as S and C may be had from the above mentioned patent it will be assumed that the line associated with station P has been seized and that the subscribers therat signalled in the manner fully described in the above mentioned patent.

In response to the actuation of the substitution bell, the called subscriber removes the receiver from the switchhook, whereupon relay 153 of connector C is actuated. The operation of this relay reverses battery and ground back over the connection so that polar relay 45 operates to connect relay 47 across the tip and ring of the manual end of the trunk E. It will be understood that where the connection was established the current through the windings of relay 45 was of such a direction as to prevent its operation at that time. A circuit now exists which may be traced from grounded battery, through the winding of relay 39, front contact and right hand armature of relay 36, lower right hand winding of repeating coil 19, front contact and inner armature of relay 22, lower normal contacts of keys 92, 52 and 40, ring contacts of plug 30 and jack 31, conductor 85, contact and armature of relay 45, back contact and inner lower

10 armature of relay 43, winding of relay 47
 15 tip contacts of jack 31 and plug 30, upper
 alternate contacts of relay 33, upper normal
 contacts of keys 40, 52 and 92, outer armature
 20 and front contact of relay 22, upper
 right hand winding of repeating coil 19,
 inner left hand armature and front contact
 25 of relay 36 to ground. Relay 39 operates
 in series with relay 47 in this circuit. Lamp
 30 33 is thereby shunted by the low resistance
 path to battery through resistance 180. Relay
 47 in attracting its armature disconnects
 35 cut-off relay 43 from the ring side of
 the line to balance the connection for talking
 purposes. The extinguishment of lamp
 40 53 informs the operator that the called party
 has responded.

45 It will be noted that when the operator
 actuated the dialing key 40, the cord circuit
 was split, that is, there was no electrical
 connection between the calling end and the
 answering end so that should the operator
 50 fail to restore the dialing key 40 and the
 called party had responded, there would
 be no talking connection set up so that
 conversation would be impossible. To avoid
 55 such a condition, applicant has provided an
 arrangement whereby the operator is given
 an audible warning signal should she fail
 to restore the dialing key. Assuming that
 60 the dialing key is actuated and that relay
 45 has operated in response to the current
 reversal caused by the response of the called
 subscriber, a circuit may be traced from
 65 grounded battery, winding of relay 29, back
 contact and inner right hand armature of
 relay 49, off-normal contact 181 of dial Q,
 left hand armature and back contact of
 70 relay 49, conductor 48, lower alternate
 contact of key 40, ring contacts of plug 30 and
 jack 31, conductor 85, contact and armature
 of polar relay 45, back contact and armature
 75 of relay 43, winding of relay 47, tip
 contacts of jack 31, and plug 30, upper
 normal contacts of relay 33, upper alternate
 contacts of key 40, conductor 95, pulsing
 80 contact 54 of dial Q to ground over the
 outer right hand armature and back contact
 of relay 50. Relays 47 and 29 operate in
 85 this circuit. Relay 47 performs the same
 function as hereinbefore described. Relay
 29 in operating connects a tone signal source
 90 to the operator's headset. On hearing
 95 this signal the operator knows that the
 called party has responded and that she has
 failed to restore the dial key. She will
 100 thereupon restore the key, releasing relay
 29, cutting off the tone signal and conditioning
 the cord circuit for talking purposes.
 105 At the termination of the conversation, the
 called party hangs up the receiver whereupon
 110 relay 153 releases restoring the original
 condition of battery and ground to the
 connection so that polar relay 45 again
 115 attracts its armature, this time in the opposite

115 direction thereby opening the bridge including
 120 relay 47 across the manual end of the
 trunk. The opening of this bridge releases
 125 relay 39 whereupon the shunt is removed
 from lamp 53 and it is again illuminated in
 130 indicating to the operator that the conversation
 has ceased and that she may proceed
 135 to take down the connection. Should the
 calling subscriber at station A restore the
 140 receiver before the plug 13 is removed from
 jack 14, relay 18 would be released and lamp
 145 20 would thereupon be illuminated.

150 When the operator removes plug 30 from
 jack 31, relay 38 releases which in turn re-
 leases relay 41. Relay 41 in releasing,
 155 opens the locking circuit for relay 42 which
 thereupon restores its armatures releasing
 160 relay 44 and cutting off the protective
 bridge. Relay 44 in releasing, opens up the
 165 holding bridge to the automatic end of the
 connection, whereupon the switches restore
 170 in the well known manner. The removal of
 plug 13 from jack 14 releases relays 11, 16
 and 15. Relay 11 reconnects the line relay
 175 10 to the line A, whereas relay 15 opens up
 180 the energizing circuits for relays 22, 23, 18
 and 21, which thereupon releases restoring
 185 the circuit to normal condition.

190 If the operator at any time during the
 195 period of conversation desires to listen in on
 the connection, she actuates the monitoring
 key M, whereupon a circuit is established
 200 extending from grounded battery through
 the winding of relay 25, conductor 26, to
 ground over the upper alternate contacts
 205 of key M. At its other contacts, key M con-
 nects the conductors 28 and 27 to the tip and
 ring conductors of the cord circuit, these
 210 conductors being normally associated with
 the operator's telephone set by way of the
 215 back contacts and armatures of relay 29.
 Relay 25, operating in the circuit just de-
 scribed, disconnects the operator's transmitting
 220 circuit from her receiver, and connects
 the receiver directly to the armatures of re-
 225 lay 29. The operation of relay 25, there-
 fore, disconnects the operator's transmitting
 circuit from the receiving circuit and con-
 nects the receiving circuit directly across the
 230 talking conductors of the established connec-
 235 tion. In this manner, the operator may
 listen in on the connection without disturbing
 240 the talking parties.

245 Referring now to the establishment of a
 toll switching connection, which includes
 250 Figs. 1, 2, 4 and 5. With Fig. 4 placed be-
 tween Figs. 1 and 5 and Fig. 2 immediately
 255 above Fig. 1, the operation is as follows:—

260 Assuming that the call originates at the
 magneto station B, the subscriber thereat re-
 moves the receiver from the switchhook and
 265 actuates the magneto to send out current
 over the line loop in order to actuate the
 drop or line signal 60. Upon noting the ac-
 tuated drop, the operator inserts plug 13 into
 270

jack 59 and operates her talking key T. The calling line being of the magneto type, has a relatively high resistance sleeve. Upon the insertion of plug 13 into jack 59, drop 60 5 is removed from the line and a circuit is established which may be traced from grounded battery, through the winding of relay 15, winding of relay 16, sleeve contacts of plug 13 and jack 59 to ground. Owing to the 10 high resistance sleeve of the magneto line B marginal relay 15 does not operate in this circuit. Relay 16, however, does operate but performs no useful function at this time. Relay 17 is now bridged across the repeating 15 coil 19 and is employed for supervisory purposes as will hereinafter appear. Lamp 20 does not light at this time.

The actuation of talking key T performs the same function as described in the previous connection, that is, to connect the operator's telephone set with the calling line. The operator now converses with the calling subscriber in order to ascertain the number of the desired line. Upon learning that a 25 connection is desired with the party located at station R, the operator tests for a busy toll switching trunk in the same manner as described in the testing for an idle local trunk. Assuming the trunk, Fig. 4, to be an idle toll 30 switching trunk the operator inserts plug 30 into jack 61 whereupon a circuit is established which may be traced from grounded battery, winding of relay 36, winding of relay 37, sleeve contacts of plug 30 and jack 61 35 to ground through the winding of high resistance relay 62. Relay 36 being marginal does not operate in this circuit. Relays 37 and 62, however, operate, the former, establishing an obvious circuit for relay 33 and 40 connecting ground to the middle alternate contact of dial key 40, by way of the outer left hand armature and back contact of relay 36. Relay 33 in operating, disconnects the 45 busy test relay 32 from the tip of the calling cord and renders the tip conductor of the cord continuous at that point. The operation of relay 62 performs no immediate function. A circuit may now be traced from grounded battery, through high resistance 50 element 79, through the left hand winding of relay 65, back contact and outer lower armature of relay 69, ring contacts of jack 61 and plug 30, lower normal contacts of keys 40, 52 and 92, inner armature and back contact of relay 22, lower left hand winding of 55 repeating coil 19, winding of marginal relay 75, upper left hand winding of repeating coil 19, back contact and outer armature of relay 22, upper normal contacts of keys 92, 52 and 40, upper alternate contacts of relay 33, tip contacts of plug 30 and jack 61, upper inner normal contacts of relay 69 to ground through marginal relay 64. Owing to the 60 inclusion of resistance element 79 in this circuit, marginal relays 64 and 75 do not operate. Relay 65, however, operates and in attracting its armature establishes a bridge for the mechanical switching end of the trunk, which prepares the selector switch D for stepping. This bridge may be traced 65 from conductor 83, winding of relay 70, outer armature and back contact of relay 71, right hand winding of relay 65, back contact and outer right hand armature of relay 68, 70 armature and front contact of relay 65, windings of polar relay 63, front contact and inner armature of relay 62, to conductor 84. The operator now actuates the dial 40 whereupon a circuit is established which may be traced from grounded battery, through 75 the winding of relay 49, conductor 88, middle alternate contact of key 40, back contact and outer left hand armature of relay 36, to ground over the front contact and armature of relay 37. Relay 49 operates in this circuit and in attracting its armature connects ground to the off-normal spring of dial Q, opens the circuit for relay 29, connects ground to the ring side of the cord and establishes an obvious circuit for relay 50. 80 Relay 50 operates and at its outer right hand armature and front contact substitutes battery for the ground normally connected to the pulsing contact of dial Q. The resistance of the tip circuit is now such as to 85 permit relay 64 to operate in a circuit extending from grounded battery, front contact and outer right hand armature of relay 50, pulsing contact 54 of dial Q, conductor 95, upper alternate contacts of dial key 40, upper alternate contacts of relay 33, tip contacts of plug 30 and jack 61, upper inner normal contacts of relay 69, to ground 90 through the winding of relay 64. Relay 64 operates in this circuit and in attracting its 95 left hand armature connects relay 70 across the mechanical end of the toll switching trunk in parallel with the right hand winding of relay 65 and windings of relay 63. In attracting its right hand armature, relay 64 causes relay 67 to operate in a 100 circuit extending from grounded battery, inner armature and back contact of relay 71, right hand armature and front contact of relay 64, back contact and outer left hand 105 armature of relay 68, winding of slow-release relay 67, to ground over lower inner normal contacts of relay 69. Relay 67 in operating, establishes a circuit for relay 68 which may be traced from grounded battery, 110 winding of relay 68, armature and front contact of relay 67, middle armature and front contact of relay 62 to ground. Relay 68 in attracting its inner left hand armature locks itself to ground on the middle 115 armature of relay 62. At its outer left hand armature, relay 68 transfers the winding of relay 67 from the back contact to the 120 125

front contact, slow-to-release relay 67 holding up during this transfer. Relay 68 performs no other function at this time.

The operator now moves the dial Q off normal whereupon the ground is removed from the off-normal spring and hence from the ring side of the connection thereby causing relay 65 to release, which thereupon removes one of the bridges including its own right hand winding and the windings of polar relay 62 from the mechanical end of the trunk. The operator then releases the dial Q which in returning to normal interrupts the circuit of the impulse relay 64 which, at its left hand armature opens the bridge including the winding of relay 70, thereby operating relay A₃, a number of times corresponding to the first digit of the desired number. Relay 67 being slow-to-release, holds up during the operations of relay 64.

Since the operations of the automatic switches schematically represented at D, H and K do not enter into the present invention it is believed unnecessary to enter into a detailed description of these operations in this application. A complete description of the operations of such switches may be had by referring to a copending application of R. L. Stokely, Serial No. 412,795, filed September 25, 1920. It will suffice to say that these switches are controlled by the succeeding digits sent out by the operator to connect the terminals of the toll switching trunk with the terminals of the desired line, in a manner fully described in the above mentioned copending application.

After the transmission of all digits, relay 65 remains operated over the ring side of the connection to ground in the dialing equipment, or if the dialing key is restored to normal, as will be the usual condition, over the cord circuit bridge including the winding of relay 75. The release of the dial key removes the dialing equipment from the cord and renders the talking conductors of the cord circuit electrically continuous.

In accordance with general practice, and as described in the above mentioned copending application, the seizure of an idle line R will effect the reversal of current over the trunk N, whereupon polarized relay 63 responds. Relay 63 in operating, causes relay 69 to operate in an obvious circuit. Relay 69 in attracting its armatures, disconnects relays 64 and 65 from across the tip and ring conductors of the trunk, opens the energizing circuit for relay 67, extends the tip and ring conductors of the trunk to the automatic switches and locks itself to ground by way of the inner right hand armature of relay 68. By removing relays 64 and 65 and high resistance 79 from across the trunk conductors, battery and ground are also re-

moved so that marginal relay 75, which is bridged across the cord circuit, may now operate in a circuit including grounded battery, left hand winding of relay A-5, right hand alternate contacts of relay F-4, conductor 83, inner upper alternate contacts of relay 69, tip contacts of jack 61 and plug 30, upper alternate contacts of relay 33, upper normal contacts of keys 40, 52 and 92, outer armature and back contact of relay 22, upper left hand winding of repeating coil 19, winding of relay 75, lower left hand winding of repeating coil 19, back contact and inner armature of relay 22, lower normal contacts of keys 92, 52 and 40, ring contacts of plug 30 and jack 61, outer lower armature and front contact of relay 69, conductor 84 left hand alternate contacts of relay A-5 and ground at the right hand winding of relay A-5. Relay 75, owing to the low resistance of the circuit just traced, operates and establishes an obvious circuit for lamp 53. The illumination of lamp 53 at this time serves as a ringing signal to the operator. The operator upon noting this signal actuates the ringing key 52 to signal the called subscriber in a manner fully described in the above mentioned copending application. When the called subscriber answers, the ringing current is automatically disconnected from the line in the well known manner. The removal of the receiver at the called station R also causes supervisory relay 75, which corresponds to relay B-43 of the above mentioned copending application, to be released in the same manner as described in that application in connection with the release of relay B-43. Relay 75 upon deenergizing extinguishes the lamp 53. At the termination of the conversation, the restoration of the receiver at station R causes relay 75 to operate and energize the lamp 53 as a disconnect signal. The operator upon noting the illumination of lamp 53 may proceed to take down the connection. A disconnect signal may also be given by the calling subscriber in actuating the magneto associated with the station R. Current from the magneto causes relay 17 which is bridged across the answering end of the cord circuit to operate, establishing an energizing circuit for relay 21. Relay 21 operates establishing a locking circuit for itself and an energizing circuit for lamp 20 which may be traced from grounded battery, through the filament of lamp 20, left hand winding of relay 21, front contact and armature of relay 21, front contact and armature of relay 16, to ground over the upper normal contacts of talking key T. The operator may extinguish the lamp 20 by actuating her talking key T or by withdrawing plug 13 from jack 59. The actuation of the magneto in the manner just described may also serve as a recall sig- 130

nal to the operator who then actuates the said dialing equipment to function with the trunk circuit employed.

5. The operator takes down the connection by removing plugs 30 and 13 from jacks 61 and 59, respectively. The removal of plug 30 from jack 61 causes relays 62 and 37 to release. Relay 62 in releasing, opens the 10 locking circuit for relay 68 which in turn releases and opens the locking circuit for relay 69 restoring the trunk circuit to normal. The automatic switches are released in the usual manner as described in detail in the 15 above mentioned copending application. When removing plug 13 from jack 59, the operator causes relay 16 to release, this relay being the only relay operated at this time.

The operator may listen in during the 20 period of conversation in the same manner as described in connection with the local connection.

What is claimed is:

1. In a telephone system, a plurality of 25 trunk circuits having different dialing characteristics, a cord circuit, a dial circuit for supplying different dialing potentials, a key for connecting the dial circuit to the cord, and means operative in response to the connection of said cord circuit with one of said 30 trunk circuits and the actuation of said key for conditioning said dial circuit to supply the particular dialing potential required for the trunk circuit taken for use.

35. 2. In a telephone system, a plurality of trunk circuits requiring different potentials for dialing thereover, a cord circuit, the dialing circuit associated therewith for supplying different dialing potentials, and means effective subsequent to the association of said cord circuit with any of said 40 trunk circuits for selecting at said dialing circuit the potential required by the trunk circuit employed.

45. 3. In a telephone system, a plurality of trunk circuits, a relay for each of said trunk circuits, each relay requiring a different connection of current to effect its operation, a cord circuit, a dial, a battery and circuits therefor for connecting said battery through one pole or the other to said dial, and means 50 operative in response to the association of said cord circuit and said dial with any of said trunk circuits for selecting the proper pole of the battery to cause the operation of the relay associated with the trunk circuit employed.

55. 4. In a telephone system, a cord circuit adapted to function with a plurality of trunk circuits, each of said trunk circuits requiring a different polarity for dialing thereover, dialing equipment, and discriminating means associated with said cord circuit and responsive to the association of said cord with any of said trunk circuits for conditioning

5. In a telephone system, a local trunk, a toll switching trunk, a dialing circuit adapted to function in a different manner 70 with each of said trunks, a cord circuit, and means associated with said cord circuit for discriminating between said local and toll switching trunks to condition said dial circuit to function therewith. 75

6. In combination, a dialing circuit adapted to supply different polarities for dialing, different types of connecting trunks for association therewith functioning in response to different polarities and means responsive on the connection of the dialing circuit with any trunk circuit to cause the polarity required in each case to be supplied by the dialing circuit. 80

7. In combination, a dial circuit adapted 85 to supply different polarities for dialing, a cord circuit associated therewith, different types of connecting trunks for association with said dial circuit through said cord circuit and means associated with said cord 90 circuit responsive to the connection of the cord circuit with a trunk to cause the polarity required in each case to be supplied by the dial circuit.

8. In combination, a dial circuit adapted 95 to supply different potentials for dialing over different connections, a cord circuit, and a marginal relay associated with said cord circuit for discriminating between the different connections to supply the required 100 potential.

9. In a telephone system, a subscriber's station, a connection thereto including a cord circuit and a plurality of connecting links, a dial circuit, an operator's receiver associated therewith, means for associating said dial circuit with said cord, and means responsive to the removal of the receiver at said station and the operation of said first means for connecting a source of 110 current to said receiver. 105

10. In a telephone system, a substation, a connection thereto including a cord circuit and a plurality of connecting links, a dial circuit, an operator's headset, means for associating said dial circuit with said cord, a source of tone current, and means responsive to the removal of the receiver at said station and the operation of said first means for connecting said tone current 115 to said headset. 120

11. In a telephone system, subscriber stations, a connection between two subscriber stations including a cord circuit and a plurality of connecting links, an operator's position, means for splitting said cord circuit during and after the establishment of said connection, and means responsive to the removal of the receiver at one of the stations in the connection for indicating to 125 130

an operator at said position the split condition of said cord circuit.

12. In a telephone system, subscriber stations, a connection between two subscriber stations including a cord circuit and a plurality of connecting links, an operator's position, means for splitting said cord circuit during and after the establishment of said connection, signaling means, and means 10 responsive to the removal of the receiver at one of the stations in the connection for operating said signaling means thereby indicating to an operator at said position the split condition of said cord.
13. In a telephone system, a subscriber's station, a connection thereto including a cord circuit and a plurality of connecting links, an operator's receiver, a source of tone current, means for splitting said cord circuit 15 during the establishment of said connection, and means responsive to the removal of the receiver at said station for connecting said tone current with said operator's receiver to indicate to the operator the 20 split condition of said cord circuit.
14. In a telephone system, substations, a connection between two substations including a cord circuit and a plurality of connecting links, an operator's position, means for splitting said cord circuit during and 25 after the establishment of said connection, and means controlled from one of the substations in the connection for indicating to an operator at said position the split condition of said cord circuit. 30

15. In a telephone system, a substation, a connection thereto including a cord circuit and a trunk circuit, a pulsing relay for said trunk circuit, a dial, a dial key, means operative over the ring side of said 35 trunk for energizing said relay, and means responsive to the off-normal actuation of said dial subsequent to the operation of said key for connecting the relay to the tip side of said trunk. 40

In witness whereof, I hereunto subscribe my name this 17th day of August A. D., 1923.

CLARENCE B. FOWLER.
